UNITED STATES PATENT OFFICE

CHARLES C. SCHRADER, OF LANCASTER, PENNSYLVANIA, ASSIGNOR TO ARMSTRONG CORK COMPANY, OF LANCASTER, PENNSYLVANIA, A CORPORATION OF PENNSYLVANIA

CORK BOARD INSULATION AND METHOD OF ERECTING THE SAME

Application filed February 28, 1930. Serial No. 432,063.

This invention relates to a corkboard insulation and a method of erecting the same. In the erection of corkboard against a masonry, concrete or brick wall, as, for example, in the construction of refrigerating rooms, the common practice is to apply a plaster coat to the inside surface of the wall, thus forming a plane surface to which the insulation is applied, followed by the use of an asphalt paint 10 on the plaster to serve as a bond for securing the corkboard to the wall. Asphalt is also used on the corkboard itself. The asphalt on the board is applied by hot dipping, but since the wall is cold, the asphalt will congeal without forming a good key to the wall unless the wall has been painted, as above stated. The great difficulty with this method of erection is the impossibility of getting adequate contact between the board and the wall throughout the area of the board. However careful a plasterer is, the wall will have irregularities deeper than the paint coat. The asphalt dip on the board is, therefore, called upon to flow laterally along the board if these irregularities 20 in the wall are to be filled. The asphalt on the board hardens almost immediately upon contact with the painted wall. As a result, contact is had, usually, at the high points only on the wall. Another difficulty 25 is the failure of the film of asphalt paint in high walls. Due to the decreased contact area, the stress induced in the effective paint film is frequently greater than it will bear. Where the wall is higher than about 14 feet, 30 additional mechanical support is usually supplied. Since some insulation walls have a height as much as 50 feet, it will be seen that a ready means of erecting corkboard so that each block or slab will adhere firmly is a marked improvement over the method now 35 generally in vogue.

I provide for applying a cementitious coating to the surface of the board, placing the board against the base wall with the coating innermost, and permitting the coating to harden. Preferably, provision is made for mechanically keying the board to the cementitious coating. Ordinarily it will not be practicable to shape the surface of the corkboard so as to obtain such keying, first, for

the reason that the slabs are sawn from large blocks and a special shaping would involve additional operations, and second, because, as hereinafter stated, I prefer to use a corkboard which is specially treated, and such treatment is rendered more difficult with a non-planar surface. I therefore preferably employ keys in the form of hangers which are secured to the corkboard and which have projecting portions embedded in the cementitious coating. For example, I may employ 60 nails which are driven into the corkboard but left with their heads projecting a short distance, the heads being embedded in the cementitious coating.

Ordinary corkboard is attacked by the free lime present in wet plaster. I therefore prefer to employ a corkboard which is adequately sealed against moisture penetration. In the copending application of Lester E. Cover, 70 Serial No. 414,435, filed December 16, 1929, there is described and claimed a corkboard having its outer particles embedded in a matrix, which matrix may extend to considerable depth and is effective for sealing the 75 board against moisture and air infiltration, and to which plaster will bond. Such matrix may be formed of a relatively high-melting-point asphalt. An asphalt having a melting point of 220° F. has been used successfully. 80 If desired, the matrix may be applied as an emulsion. Any of the usual emulsifying agents, such as soap, glue, clay or the like, may be employed. If an emulsion is used, the matrix should have a melting point below 85 212° F., as a low-melting-point asphalt emulsifies better than one having a high melting point. An asphalt having a melting point of about 180° F. will prove satisfactory. I preferably employ corkboard manufactured according to the said Cover application.

In the accompanying drawing illustrating the present preferred embodiment of the invention,

Figure 1 is a broken perspective view illustrating an insulation wall;

Figure 2 is a sectional view showing the manner of applying the cementitious coating to the corkboard; and

Figure 3 is a view to enlarged scale showing one of the hangers in the corkboard.

The insulating wall shown in Figure 1 comprises a base wall 2 of brickwork, a layer 3 of plaster, a layer 4 of corkboard, a layer 5 of corkboard, and a face coating 6 of asphalt or the like. In applying the layer 4 of corkboard to the base wall 2, each slab 7 of corkboard is first provided with hangers 8 in the form of hook-like nails. Any desired number of these nails is driven into each slab of corkboard, the heads being allowed to project, as shown in the drawing. In order to preserve the nails against attack and to prevent ingress of moisture therearound, each nail, before driving, is dipped in asphalt, the result being that the protruding portion of the shank, as well as the nail head, is covered with a layer 9 of asphalt, as shown 20 in Figure 3.

The corkboard employed is preferably of the type described and claimed in the Cover application, above referred to, and in the drawing I have shown heavy cross hatching 25 adjacent the edges of the board to indicate the depth of penetration of the mastic which forms a matrix for the outer particles. This matrix seals the board against infiltration of air, and coupled with the coating on the projecting nail heads, gives protection to the entire surface.

Each corkboard slab with its projecting nails uppermost is fed through a guide 10 under a doctor blade 11 with a mass of Portland cement plaster P therebehind. This gives a coat 3W of wet plaster over the surface of the corkboard, the projecting heads of the binder nails 8 being embedded therein. The slab is then pushed against the wall and supported until the plaster dries. The plaster adheres readily to the base wall 2 and also adheres to the corkboard 4. This adherence is due not only to the presence of the hangers 8, but also to a general adherence over the surface of the corkboard, which adherence may be enhanced by mechanical interlocking with pits or depressions in the surface.

After the layer 4 of corkboard has been put in place, the layer 5 is applied in the usual fashion by applying asphalt to one surface of the slabs forming the layer 5, pressing them against the layer 4, while breaking joints, and driving nails 12 into the layer 4.

I have illustrated at 6 a facing coat which may be of asphalt or the like. In certain cases this may be omitted and the joints alone treated. If a single thickness wall is required, a coating may be applied to the exposed face of the layer 4, or the joints alone of this layer may be treated.

The plaster layer employed will generally be about $\frac{1}{2}$ inch thick, and the nails will be allowed to project about $\frac{3}{8}$ ths of an inch. I have successfully supported 12 inch by 36 inch

slabs by employing six nails, but with nails of the ordinary type in very light corkboard, there is a tendency, when the cork is exposed to extreme test conditions, for the nails to cut through the cork. For this reason I prefer to use the flat hook-like nails shown in the drawing. Whatever type of nails be employed, they may advantageously be formed of rustless or non-corroding material.

A great advantage of my invention is that the corkboards may be placed against the wall and worked into position much more easily than under the present method where an asphalt paint is employed. In addition, there are substantially no void spaces between the corkboard and the wall where moisture may condense. The invention is applicable to other types of corkboard, but provision should be made for sealing the cork against the attack of free lime in the plaster.

I have illustrated and described a present preferred form of the invention. It will be understood, however, that this is by way of illustration only, and that the invention may be otherwise embodied or practiced within the scope of the appended claims.

I claim:

1. An insulating structure comprising a base, a hardened cementitious facing, corkboard over the facing, and ties bedded in the facing and extending into the corkboard.

2. An insulating structure comprising a wall of brick or the like, a hardened cementitious facing, corkboard over the facing, and ties bedded in the facing and secured to the corkboard.

3. An insulating structure comprising a corkboard facing, bracing nails extending into the corkboard, the nails having portions projecting outwardly from the corkboard and supports engaging the projecting portions of the nails.

4. An insulating structure comprising a corkboard facing, hangers extending into the corkboard and having flattened top faces, portions of the hangers projecting beyond the corkboard, and supporting means engaging said projecting portions.

5. An insulating structure comprising a corkboard facing, hangers extending into the corkboard and having flattened top faces, portions of the hangers projecting beyond the corkboard, and supporting means engaging said projecting portions, said supporting means engaging the surface of the corkboard.

6. An insulating structure comprising a base, a hardened cementitious facing adherent thereto, and corkboard over the facing and in contact therewith, the corkboard constituting particles of cork, those particles in the corkboard adjacent the cementitious facing being embedded in a matrix, which matrix contacts with the cementitious facing and protects the particles therefrom.

7. An insulating structure comprising a

base, a hardened cementitious facing adherent thereto, and corkboard over the facing and in contact therewith, the corkboard constituting particles of cork, those particles in the corkboard adjacent the cementitious facing being embedded in an asphaltic matrix, which asphaltic matrix contacts with the cementitious facing and protects the particles therefrom.

10 8. In the method of erecting corkboard treated to prevent attack by plaster, the steps consisting in applying a coating of wet lime-containing plaster to the surface of the board, placing the board against a base with the 15 coating in contact with the base and supporting the board in position until the plaster hardens.

9. In the method of erecting corkboard treated to prevent attack by plaster, the steps 20 consisting in securing a hanger to the board, bedding the projecting portion of the hanger in a coating of wet plaster spread over the surface of the board, placing the board against a base while the plaster is wet and 25 maintaining it in contact with the base while the plaster hardens.

In testimony whereof I have hereunto set
my hand.

CHARLES C. SCHRADER.
